UNITED STATES PATENT OFFICE.

RUSSELL H. BURR, OF WEST MERIDEN, CONNECTICUT, ASSIGNOR TO
C. ROGERS & BROS., OF SAME PLACE.

DESIGN FOR COFFIN-SCREW HEADS.

Specification forming part of Design No. 8,038, dated February 2, 1875; application filed January 22, 1875.
[Term of Patent 7 years.]

CASE B.

To all whom it may concern:

Be it known that I, RUSSELL H. BURR, of West Meriden, in the county of New Haven and State of Connecticut, have invented a new Design for Coffin-Screw Head; and I do hereby declare the following, when taken in connection with the accompanying drawings and the letters of reference marked thereon, to be a full, clear, and exact description of the same, and which said drawings constitute part of this specification, and represent, in—

Figure 1, plan or top view; Fig. 2, side or front view.

This invention relates to a design for the heads of coffin-screws—that is, the screws by which the tops of coffins are secured; and the invention consists, first, in a flat head of “honeysuckle” shape; second, in the peculiar outline form of the screw-plate, as shown in the accompanying illustration.

The screw-head consists of a base, *a*, from

which spring two branches—one turning to the right, the other to the left—their upper end turned inward to a center, the whole presenting two flat faces. The screw-plate is, in general outline, elliptical, the edges broken by circular recesses, as shown.

The plate and screw, while intended to be used together, may be used separately—that is, the plate with a different head, and vice versa.

I claim—

1. The design for coffin-screw head, as herein described, and shown in the accompanying illustration.

2. The design for coffin-screw plate, as herein described, and shown in the accompanying illustration.

RUSSELL H. BURR.
